(57) **CLAIM**

The ornamental design for a general purpose engine, as shown and described.

DESCRIPTION

FIG. 1 is a front elevation view of a general purpose engine, showing our new design;

FIG. 2 is a rear elevation view thereof;

FIG. 3 is a left side elevation view thereof;

FIG. 4 is a right side elevation view thereof;

FIG. 5 is a top view thereof;

FIG. 6 is a bottom view thereof;

FIG. 7 is an upper left rear perspective view thereof;

FIG. 8 is an upper right front perspective view thereof;

FIG. 9 is a lower left front perspective view thereof; and,

FIG. 10 is a lower right rear perspective view thereof.

In the drawings, the broken lines shown in FIGS. 1, 2, 4 and 5 depict unclaimed subject matter only and form no part of the claimed design.
